14 Claims. (Cl. 32—5)

The invention relates to a device for elastically connecting partial artificial dentures with the remaining natural teeth or with each other.

It is known to construct especially partial, but also complete, artificial dentures, particularly those made of plastics, in one piece. They are supported on the mucous membrane or gum and the partial dentures are detachably anchored to the remaining natural teeth by means of clasps. Experience shows that these artificial dentures have a tendency to damage the remaining natural teeth, in particular those serving as anchors because the mucous membrane of the jaw yields with any chewing pressure exerted on the artificial denture. As this occurs, tilting movements of the artificial denture are created which are transferred to the anchor teeth through the connecting clasps.

Very often the remaining natural teeth are constituted by the incisors and the individual bicuspids so that the molars must be replaced by so-called free saddles, the artificial denture then having its end freely supported on the alveolar ridge of the edentated jaw portion. Here the free saddles are depressed especially during the chewing action owing to the yielding character of the mucous membranes, and this tilting movement is resisted solely by the incisors of the remaining natural teeth, in particular, the teeth carrying the clasps. These stresses lead to a loosening of the anchor teeth. In addition, these teeth are damaged by the friction of the clasps to such an extent that pain is caused by the exposed dentine. Furthermore, the incidence of caries in such teeth is high.

In many cases, the loss of the molars is confined to one side so that holders may be fitted to the remaining natural teeth at which the free end saddles are connected with joints. Mostly, steel plates are used for this purpose. The result of this pivotal connection is that the free end saddles may swing away at their ends but not at the point of connection to the artificial denture or crown to which they are attached.

It has been found that a substantial percentage of patients decline to wear an artificial denture made in one piece because the aforescribed phenomena are disturbing to a point where the patients forego tooth replacement rather than have their remaining natural teeth destroyed. In addition, a replacement with pivotable connections at the metal plates is relatively expensive and is therefore out of the question for broad strata of the people. Furthermore, when designing the teeth in case of a replacement on a free end saddle which is pivotally connected with a steel plate or a crown, one has to take into consideration the effects of the chewing pressure because this free end saddle can press itself only into one end of the deformed mucous membrane. It is therefore necessary that the last molars be made smaller so that the chewing pressure is relieved at this location.

In order to avoid these disadvantages, and in accordance with the invention, I provide a fastening device for partial artificial dentures made of plastics in which the connection between the artificial teeth and the remaining natural teeth is made resilient so that the chewing pressure effective, for instance, on one free end saddle cannot be transferred to the remaining natural teeth. In accordance with the invention, a guiding pin made of spring wire and fastened to the remaining natural teeth

2

projects for this purpose into the artificial denture and is enclosed adjacent thereto by a sleeve which may be embedded in the artificial denture, a coil spring being disposed in the space between the guiding pin and the sleeve and tensioned between an abutment on the sleeve and an abutment on the guiding pin, with at least one pair of coating formations being provided on the sleeve and on the guiding pin to prevent a relaxation of the spring. An extension of the pin extending endwise from the sleeve, such as a spring wire integral with that pin, is thus limitedly movable in outward direction against the spring force, this extension being anchored to an external support such as a natural tooth or another partial denture.

In a preferred embodiment of the invention two such spring guides are embedded in the artificial plastics denture in such a manner that the sleeves provided with stressed springs are disposed laterally along the ridge on both sides thereof. One end of the spring-guiding pins is arranged to embrace the remaining natural teeth in a manner known per se or to be fastened with an intermediate piece of a plastic material serving to anchor the partial artificial denture to the remaining natural teeth. If the molars are to be replaced on both sides, it is proposed that the spring pin constitute a terminal portion of a flexible elongated tension element, such as a wire, extending lingually behind the incisors from one spring sleeve, embedded in one partial denture, to another spring sleeve, embedded in the other partial denture, the intermediate portion of the guide wire being embedded in a plastic armor or sheath separating the two partial artificial dentures in which the pin-shaped extremities of the wire are concealed. This plastic armor is then secured to the remaining natural teeth with the aid of arcuate clasps which are likewise embedded in the plastic armor and the free ends of which detachably surround the residual natural teeth.

I further propose particularly in connection with smaller partial artificial dentures, to connect two approximately parallel guide pins, encased in coil springs and sleeves, with metallic tooth crowns by attaching to said crowns a releasable holding device for the guiding pins. By virtue of this flexible and resiliently yieldable linkage between the remaining natural teeth and the partial artificial denture, the force exerted under pressure, e.g. during chewing, is not transmitted to the remaining natural teeth through the connecting piece proper because the artificial denture is movable within certain limits with respect to its holding arrangement. The coil spring compressed between the sleeve and the guide pin allows for an elastic axial displacement between the guide pin and the sleeve and thus between the artificial denture and its support in a manner permitting limited separation of the denture from the support against its biasing force, this force being inwardly directed with reference to the tooth carrier in which the sleeve is embedded.

The stored force of the stressed spring is absorbed by its end stops so that no stresses are exerted on the partial artificial denture and the remaining natural teeth. In order to permit adaptation to the requirements of a complete artificial denture, the sleeve is provided with a certain clearance with respect to the guiding pin which is determined by the resiliency of the mucous membranes. It has proved to be advantageous to make the inner diameter of the sleeve 2 mm because the resiliency of the mucous membrane allows it to yield by about 0.7 to 1 mm. In this manner, the partial artificial denture is rendered freely movable in any direction within the limits desired, without being unduly loosely seated on the ridge. Therefore, the patient when chewing has the impression of biting on his own teeth.

The invention may also serve to improve the fastening of a full artificial denture in that the denture is made of

several parts which are elastically interconnected. Thus, the complete denture may be made of three parts, the middle one of which is fastened in a manner known per se by a suction press-fit onto the corresponding alveolar ridge of the jaw. This middle portion serves to secure the guiding pins whose ends are then again provided with the aforementioned abutments and coil springs for elastically holding two partial artificial dentures carrying the replacement for the molars and under certain circumstances, also for the premolars.

Further features and details of the invention will be described with reference to the accompanying drawing in which:

FIG. 1 shows by way of example a retaining device consisting of a spring guiding pin, a coil spring and a sleeve for elastically connecting partial artificial dentures with the remaining natural teeth;

FIG. 2 is a top plan view of a three-part dental prosthesis incorporating two partial dentures each provided with a pair of retaining devices as shown in FIG. 1, the plastic carrier of each partial denture and the artificial teeth fastened thereon being shown in dot-dash lines;

FIG. 3 is a sectional view taken on line III—III of FIG. 2;

FIG. 4 is a partial sectional view taken on line IV—IV of FIG. 3; and

FIG. 5 shows a sectional view of a modified retaining device for a partial denture fastened to a metal crown.

The unit shown in FIGS. 1—4 comprises a set of spring-guiding pins 1 or bolts each formed of a wire and connected on one side with the remaining natural teeth 12 or a part of a complete artificial denture, its free end on the other side being secured in a manner to be described hereinafter, to the plastic carrier 23 or 24 of a partial artificial denture 21 or 22. The free end of each pin carries a coil spring 3 which is tensioned between an abutment 4, constituted by a nut and adjustable via a thread 2, and a restriction 6 of a sleeve 5. In this arrangement, one end of the sleeve 5 is closed by a slotted set screw 7 against which one extremity of the guide pin 1 abuts. The sleeve 5 is embedded in the plastic carrier 23 or 24 of the artificial denture and is rigidly connected therewith. By selection of the spring tension it is possible to support the horizontally disposed sleeve 5 and with it the artificial denture 21, 22 for limited, resiliently restrained motion in an axial direction with respect to the pin 1. The all-around lateral clearance provided by the sleeve 5 around the pin 1 and the spring 3 enables a radial movement of the sleeve and thus simultaneously of the artificial denture with respect to the pin 1. The embodiment illustrated by way of example shows an artificial denture consisting of three parts in a case where the molars are missing on both sides but a central remainder of the natural teeth 12 is available. The curved middle portion of the artificial denture is a plastic sheath 8 which is positioned behind the incisors 12. The tip of the threaded screw 7 and the left-hand end portion 2 of the pin 1 form a pair of abutments preventing a relaxation of the spring 3.

In accordance with FIGS. 2 and 3, two pairs of spring-guiding pins 1, provided on their free ends with springs 3 and sleeves 5, are embedded in different partial artificial dentures 21, 22. The sleeves 5 are respectively arranged in pairs on both sides of the ridge 11 in a downwardly concave plastic carrier 23, 24 for the artificial denture, this carrier straddling the alveolar ridge of the jaw (see FIG. 4) in a manner known per se to retain the artificial teeth 25, 26. The intermediate portions of the spring-guiding wires extend lingually behind the remainder of the natural teeth 12 and are embedded in the plastic armor or sheath 8. At the same time, retaining clasps 10 are embedded in this plastic armor 8 and detachably enclose with their ends the remainder of the natural teeth

12 or parts thereof. FIG. 2 shows the several retaining devices for the partial dentures 21, 22 in different mounting stages. At the top, there is shown a guide pin 1 provided with the end thread 2 and without any additions. The next-lower pin 1 is provided with a spring 3 and the rear spring abutment 4 designed as a nut. In the upper half of the lower pair, the spring 3 is already surrounded by the sleeve 5 shown in section and closed on one side by the set screw 7; and on the very bottom, there is finally shown an elevational view of the complete sleeve mounted on the one end of the pin 1. Interposed between the remainder of the natural teeth 12 and the two partial artificial dentures are layers 9 of a plastic material which remains soft. Through these plastic layers 9, the pins 1 are guided. The pins 1, the springs 3 and the sleeve 5 are shown on an enlarged scale relative to the denture for the sake of clarity. It will be apparent that the mobility of the wire elements 1 in their sleeve 5 is increased by the fact that the constriction 6 is spaced to a considerable extent, i.e. by more than one-third the length of the sleeve, from the open end of the latter which faces the anchor clamp 10.

FIG. 5 shows the elastic retaining means for a partial denture fastened to a metal crown 20. The crown 20 which is to be fastened to a tooth has soldered thereto a U-shaped yoke or journal bearing 13 which is enclosed by a second, oppositely facing U-shaped yoke or journal bearing 14. The two yokes are provided with aligned holes 15, 16 through which a screw or journal pin 17 is inserted for the connection of the yokes. On yoke 14 there are provided two substantially parallel guide pins 1 having connected to the free ends thereof coil springs 3 and sleeves 5 in accordance with FIGS. 1—3. The face 27 of the yoke 14 and the edges 28 of the sleeves 5 may serve as co-operating abutments for limiting the relaxation of the springs 3. It will be noted that the assembly 13—17 constitutes a hinge by which the projecting portions of pins 1 are pivotally linked with the anchor member 20, the pivotal axis of the hinge being perpendicular to the spring housings or sleeves 5.

In order to make possible an easy replacement of the coil springs, particularly in the case of fatigue phenomena, the sleeves 5 are provided with lateral bores 19, instead of the restriction 6, in which screws 18 are inserted in a radial direction. The springs 3 are clamped between the adjustable abutments 4 and the screws 18. The two sleeves 5 are then again embedded in a plastic denture carrier conforming to the alveolar ridge and having the false teeth fastened thereto, as explained in connection with the embodiment of FIGS. 1—4. If it is intended to replace the coil springs 3, one need only loosen the screws 18 which, incidentally, also serve the purpose of assisting in keeping the sleeves 5 in the plastic carrier of the artificial denture, the guide pins 1 may thus be withdrawn together with the springs 3 from the plastic carrier.

What I claim is:

1. A resilient unit for yieldably attaching a partial denture to a support element of a human jaw, comprising, in combination, a journal assembly including a journal pin, a first journal bearing and a second journal bearing, means for connecting said first bearing to said support element, at least one bolt substantially transverse to said journal pin connected to said second bearing, a first stop member provided on said bolt, a tubular member encircling with clearance said bolt and provided with a second stop member, a helical spring bearing on said first and second stop members and arranged in said clearance between said bolt and said tubular member, said bolt and said tubular member being provided with coacting formations for placing said spring under stress, said tubular member being adapted to be connected to said partial denture.

2. A resilient unit for yieldably attaching a partial denture to a support element of a human jaw, comprising, in combination, a journal assembly including a journal pin, a first journal bearing and a second journal bearing, means for rotatably supporting said bearings on said pin, a metal crown connected to said first bearing and adapted to be attached to a natural tooth of said human jaw, two bolts connected to said second bearing and extending substantially transverse to said journal pin and mutually parallel, threaded portions provided on said bolts, two nuts screwed onto said threaded portions and forming first stop members, two sleeves encircling with clearance said bolts and provided with second stop members, two coil springs each bearing on said screw nuts and said second stop members and arranged in a respected clearance between said bolts and said sleeves, said bolts and said sleeves being provided with coacting formations for placing said springs under tension, and sleeves being adapted to be connected to said partial denture.

3. A partial denture comprising a downwardly concave tooth carrier fitting over the alveolar ridge of an edentated jaw portion, an elongated flexible element projecting endwise from said carrier for attachment to an external support on the jaw, spring means in said carrier engaging said element with an inwardly directed biasing force, and abutment means rigid with said carrier maintaining said spring means under stress by limiting the inward displacement of said element by said biasing force, the projecting portion of said element being withdrawable from said carrier against said biasing force for enabling limited yielding of said carrier to a force tending to separate it from said support.

4. A partial denture comprising a downwardly concave tooth carrier fitting over the alveolar ridge of an edentated jaw portion, a pair of substantially parallel elongated flexible elements projecting endwise from said carrier at locations corresponding to opposite sides of said ridge for attachment to an external support on the jaw, spring means in said carrier engaging said elements with an inwardly directed biasing force, and abutment means rigid with said carrier for maintaining said spring means under stress by limiting the inward displacement of said elements by said biasing force, the projecting portions of said elements being withdrawable from said carrier against said biasing force for enabling limited yielding of said carrier to a force tending to separate it from said support.

5. A partial denture comprising a downwardly concave tooth carrier fitting over the alveolar ridge of an edentated jaw portion, at least one elongated sleeve substantially horizontally imbedded in said carrier for positioning alongside said ridge, a flexible wire projecting from said sleeve to the exterior of said carrier for attachment to an external support on the jaw and having a concealed extremity received with lateral clearance in said sleeve, and spring means in said sleeve bearing upon the latter and upon said wire with an inwardly directed biasing force, said sleeve and said wire being provided with coacting formations for maintaining said spring means under stress by limiting the inward displacement of said wire by said biasing force, the projecting portion of said wire being withdrawable from said carrier against said biasing force for enabling limited yielding of said carrier to a force tending to separate it from said support.

6. A partial denture as defined in claim 5 wherein said sleeve is provided with an internal abutment, said spring means comprising a coil spring surrounding said concealed extremity and bearing upon said abutment.

7. A partial denture as defined in claim 6 wherein said abutment comprises a constricted portion of said sleeve.

8. A partial denture as defined in claim 6 wherein said abutment comprises a screw radially inserted into said sleeve.

9. A partial denture as defined in claim 6 wherein said abutment is positioned intermediate the ends of said sleeve, thereby confining said coil spring to a region substantially shorter than said sleeve and providing a region of increased lateral mobility for said wire between said abutment and the end of said sleeve facing said support.

10. A partial denture as defined in claim 6 wherein said concealed extremity is provided with a threaded end portion and with a nut screwed onto said end portion in contact with said coil spring, said coacting formations including the tip of said threaded end portion and a set screw threaded into said sleeve for contact with said tip.

11. A partial denture comprising a downwardly concave tooth carrier fitting over the alveolar ridge of an edentated jaw portion, a pair of elongated sleeves substantially horizontally and mutually parallel imbedded in said carrier for positioning alongside said ridge on opposite sides thereof, a flexible wire projecting from each of said sleeves to the exterior of said carrier for attachment to an external support on the jaw and having a concealed extremity received with lateral clearance in the sleeve, and spring means in each sleeve bearing upon the latter and upon said wire with an inwardly directed biasing force, each sleeve and the corresponding wire being provided with coacting formations for maintaining said spring means under stress by limiting the inward displacement of said wire by said biasing force, the projecting portion of said wire being withdrawable from said carrier against said biasing force for enabling limited yielding of said carrier to a force tending to separate it from said support.

12. A partial denture comprising a downwardly concave tooth carrier fitting over the alveolar ridge of an edentated jaw portion, at least one elongated sleeve substantially horizontally imbedded in said carrier for positioning alongside said ridge, a flexible wire projecting from said sleeve to the exterior of said carrier for attachment to an external support on the jaw and having a concealed extremity received with lateral clearance in said sleeve, spring means in said sleeve bearing upon the latter and upon said wire with an inwardly directed biasing force, said sleeve and said wire being provided with coacting formations for maintaining said spring means under stress by limiting the inward displacement of said wire by said biasing force, the projecting portion of said wire being withdrawable from said carrier against said biasing force for enabling limited yielding of said carrier to a force tending to separate it from said support, anchor means engageable with said external support, and hinge means pivotally linking said projecting portion with said anchor means, said hinge means having a pivotal axis substantially transverse to said sleeve.

13. A dental prosthesis comprising a pair of partial dentures and a curved middle portion, said partial dentures including two downwardly concave tooth carriers fitting over different edentated parts of the alveolar ridge of a jaw and being interconnected by at least one flexible wire having respective extremities anchored therein, said middle portion forming a sheath around an intermediate part of said wire; spring means in said carriers engaging said extremities with an inwardly directed biasing force; and abutment means rigid with said carriers for maintaining said spring means under stress by limiting the inward displacement of said extremities by said biasing force, said partial dentures being limitedly separable from said middle portion against said biasing force.

14. A dental prosthesis comprising a pair of partial dentures and a curved middle portion, said partial dentures including two downwardly concave tooth carriers fitting over different edentated parts of the alveolar ridge of a jaw and being interconnected by at least one flexible wire having respective pin-shaped extremities anchored therein, said middle portion forming a sheath around an

intermediate part of said wire; coil springs in said carriers engaging said extremities with an inwardly directed biasing force; sleeves in said carriers forming housings around said coil springs and surrounding said pin-shaped extremities with clearance; and abutment means rigid with said sleeves for maintaining said springs under stress by limiting the inward displacement of said extremities by said biasing force, said partial dentures being limitedly separable from said middle portion against said biasing force.
